CLAIM

The ornamental design for an automobile bra with football helmet design, as shown and described.

DESCRIPTION

FIG. 1 is a front and right side perspective view of an automobile bra with football helmet design, the portions of the vehicle shown in broken lines are for illustrative purposes only and form no part of the claimed design; FIG. 2 is a front elevational view thereof; FIG. 3 is a left side elevational view thereof; and, FIG. 4 is a top plan view thereof.

No illustration of the bottom of the automobile bra with football helmet design is provided since the bottom view is plain and has no design significance.
